UNITED STATES PATENT OFFICE.

JAMES BERRY, OF STEWARTON, COUNTY OF AYR, SCOTLAND, ASSIGNOR TO
BAYLIS & CRANDALL, OF UTICA, NEW YORK.

WARP-KNITTING MACHINE.

SPECIFICATION forming part of Letters Patent No. 417,221, dated December 17, 1889.

Application filed February 16, 1887. Serial No. 227,840. (No model.) Patented in England January 17, 1887, No. 721.

To all whom it may concern:

Be it known that I, JAMES BERRY, a citizen of the United Kingdom of Great Britain and Ireland, residing at Stewarton, in the 5 county of Ayr, Scotland, have invented new and useful Improvements in Warp-Knitting Machines, (for which I have obtained a patent in Great Britain, No. 721, dated January 17, 1887;) and I do hereby declare that the following is a full, clear, and exact description, which will enable others skilled in the manufacture or art to which it relates to make and use the same.

My invention relates to knitting-machines 15 of the kind known as "warp-machines," in which a number of strands of yarn are employed and simultaneously operated on by the needles to form knitted fabrics; and it consists of several mechanical combinations 20 hereinafter particularly set forth and claimed, the whole as organized constituting an improved machine adapted for the production at a very rapid rate, and consequently at small cost, of knitted fabrics, such as Scotch 25 bonnets or caps and fashioned hosiery or parts thereof.

As represented in back elevation in Figure 1, in transverse vertical section at Fig. 2, in front elevation at Fig. 3, in end elevation at 30 Fig. 4, and in detail at Figs 5 to 17 of the accompanying drawings, the improved machine constituting my invention is composed of a framing A, carrying a needle bar or rail B, suitably grooved for the reception of the 35 knitting-needles C, which, as represented in detail at Fig. 5, are of the type known as "latch-needles," and have formed upon them at or near their mid-length projecting shoulders c, which extend into a reed or slay R at 40 the rear of the needle-bar. This reed is of the form shown by Figs. 6 and 7, and serves to guide the needles and prevent their turning in the grooves b of the needle-bar, wherein they are retained by a removable strip b', 45 extending across the face of said grooves, as shown in Fig. 8.

The needles are reciprocated vertically within the grooves b of the needle-bar by means of sliding bars D and D', the former 50 of which serves to raise and the latter to de-

press the needles, and which are connected so that they move in unison by means of a link E, so bent as to clear the sliding bar J. (See Figs. 1 and 9.) Endwise movement is communicated to the bars D and D', as here- 55 inafter described, and a vertical reciprocating movement for raising and lowering the bars D D' is communicated by a bar F, which receives its motion from eccentrics G on a rotating shaft H through eccentric-straps and 60 connecting-rods g, attached to both ends of said bar F. The sliding bars D D' lie between the grooved face of the stationary needle-bar B and the reed or slay R, and they are supported each upon carrier-bars, one d, 65 which is connected to a part of the raising-bar D, being carried on the upper edge of the bar F, the other d' being secured to straps f at the upper ends of the connecting-rods g. The one carrier d, while fitted to re- 70 ciprocate vertically, is free to slide horizontally on the bar F with the bar D, which is secured to it; but the other carrier d', being fixed to the straps f, has no horizontal movement, the bar D' being fitted to slide on 75 it. Guides f' are provided to retain the bars d d' close to the needle-bar B.

The bars D and D', which are of the form shown in front, back, and top elevations at Figs. 10 and 11 and in front and top elevations at Fig. 12, are extensible and can be varied in length, so that a greater or less number of needles may be operated, as the width of the fabric may require. This variation of the effective length of the bars D D' is ob- 80 tained by forming them each of two acting-pieces D² D² and D³ D³ upon the carriers d and d', one piece being removable from and secured to the other piece by a pin or pins d⁴, 85 passing through two or more of a series of 90 holes in them, the parts being adjustable in relation to each other by removing the pins d⁴ and replacing them after the adjustment is effected. In the case of the upper bar D' the adjusting-pin passes also through a slot 95 in the carrier-bar d' and serves as a means in the carrier-bar d' and serves as a means of attachment, while permitting of a free sliding movement of the bar D' upon its carrier.

The upper and lower edges, respectively, of 100

the raising and depressing bars D D' act upon the needles only at the deeper and extensible parts, the carriers d d' not reaching the shoulders c of the needles in their movement, and as many needles as are directly over the bar D and under the bar D' are raised and depressed at each vertical reciprocation of the bars D D'.

Each of the hooks or barbs c' of the needles in rising and descending engages one of a series of strands of yarn Y, which pass from a bank of bobbins placed at the back of the machine to and through eyes, slots, or grooves i in a yarn-carrier I, situated over the needles, and loops are thereby formed in a well-known manner. Before each ascent the raising and depressing bars D D' are shifted laterally to an extent equal to the gage (or a multiple of the gage) of the needle, and at each reciprocation one or more needles at one end drop out of action, while a corresponding number of fresh needles are brought into action at the opposite ends of the bars D D'.

In order to permit of the endwise movement of the depressing-bar D' while the end of said bar bears against the projecting shoulder of the needle adjacent to the series raised under it, a movable piece d² (see Fig. 11) is fitted at each end of the bar D', and is adapted to yield on said movement taking place, and upon the bar D' ascending and clearing said shoulder the piece d² is pressed out by the spring d³, so that it passes over the shoulder and at the next downward movement acts upon it. To prevent lifting of the needles adjacent to the ends of the raising and depressing bars, wipers e, which are fixed to and travel with the bar J, which traverses the raising and depressing bars, but have no vertical movement, are provided to bear on the shoulders of the needles adjacent to the end of each bar.

The lateral movement of the raising and depressing bars D D' and of the yarn-carrier I, which moves in unison with them, is effected by means of the bar J, connected by links j to the carrier-bar d and operated by pattern mechanism adapted to impart the requisite to-and-fro movement, which may be regular or irregular and variable, according as the same pattern or varying patterns of fabrics is or are to be produced.

The pattern mechanism in the present instance consists of a sliding plate K, (see Figs. 1, 3, and 13 to 17,) having formed in it a series of steps or notches k of a depth equal to the gage of the needles, (or a multiple of such gage.) Plate K is supported and guided by means of straps X', which pass around parallel track-bars X², said bars being supported on the frame of the machine from brackets K⁵. This plate K has an intermittent movement to the extent of one step or notch at a time imparted to it by means of a driving-piece L, to which reciprocating motion is given by means of a cam or eccentric M on a spindle m, driven by gearing h from the eccen-

tric-shaft H, the cam M being in contact with rollers m' on a slotted bar L', which embraces the spindle m and is guided by a bracket m² on the machine-frame, the driving-piece L being jointed to said bar. On each of its limbs the driving-piece L has two beveled prongs l, those on one limb being inclined upwardly and those on the other downwardly. The prongs on each limb are inclined to opposite sides, so that the incline of the prongs of each limb nearest the machine will be presented in one direction and those remote will be presented in another direction. According as the driving-piece is tilted on its joint l' toward the right or toward the left, as seen in Figs. 1, 3, and 15, it moves the plate K toward the rear or toward the front of the machine, this movement being communicated by the action of the beveled prongs l upon the pins k', which are spaced at distances apart corresponding to the length of the notches or steps k. The beveled prongs on the same sides of the limbs of the driving-piece L will intermittently move the plate K, first one acting as the piece L moves up and the other as it moves down, or vice versa, and the other prongs, when the piece L is tilted, acting similarly.

The tilting of the driving-piece L from side to side to reverse the direction of movement of the plate K is effected automatically by bell-crank l², suitably journaled, and connecting-rods l³, pivoted at each side of the driving-piece L and to the bell-crank. The bell-crank are tilted at the proper time by the upward movement of blocks l⁴, that are carried loosely by rods or wires l⁵ at diagonally-opposite sides of the plate K, and in its movement to the end of its travel are brought over vertically-reciprocating spears l⁶, operated through levers l⁷ by cams or eccentrics l⁸, said levers having rollers, as shown in Fig. 13, which rest upon the periphery of cams or eccentrics l⁸. The outer ends of the levers l⁷ are pivoted to spears l⁶ and the other ends to suitable supports on the machine-frame. The block l⁴ on one side of the plate is used to determine the extent of travel of the plate K in one direction, and that on the opposite side serves to limit the travel in the opposite direction.

Each movement or step of the plate K is equal to the width of a loop (or two or more loops) in either direction, and it communicates through the roller j' on the vertical bracket J', fixed on the end of the bar J, an endwise movement to the like extent (and to the right or left, according to the direction of movement of the plate K) to the carrier-bar d and the sliding bars D D' through the link j and to the yarn-carrier I, which latter in the present instance is connected by links i' and guide-bar I' to bracket J' on the bar J and is traversed to the same extent as the bars D D'. By suitably adjusting the blocks l⁴ and the rods l⁵ (that carry them) of the pattern mechanism to regulate

the to-and-fro movement of the pattern-plate K, the sliding bars D D', and yarn-carrier I the requisite fashioning of the fabric being knitted is obtained.

5 The yarn-carrier I, in which the grooves or eyes for the yarn or thread are spaced to correspond to the spacing of the needles, has a back-and-forward movement imparted to it in order to bring the strands of yarn across the path of movement of the needles by means of two levers N, at the upper end of which it is carried, the said levers being centered on a shaft N' and acted on at their lower ends by cams n on the shaft H. A hooked comb O, provided with a series of horizontally-fitted hooks, is carried at the upper ends of two levers P, also centered on the shaft N' and operated by cams p on the shaft H, the movement of the hooked comb being so timed that the hooks upon it pass through between the needles, and on returning draw off the loops as they are formed.

15 The yarn Y in passing from the bank of bobbins to the yarn-carrier I is led over a revoluble roller Q, fitted in a trough Q', containing an emulsion serving to oil and damp the yarn as it passes over the roller. The yarn thence passes through a reed or slay S and through weighted guide-eyes or tumblers 30 T to the yarn-carrier.

25 By the provision of the rotating roller Q and trough Q', containing the oiling and damping emulsion, the use of apparatus for oiling and damping the yarn before it is wound upon the bobbins is dispensed with.

30 The operation of the machine is as follows: Rotary motion being imparted to the main working-shaft H by means of gearing U from a toothed wheel U' upon a shaft V, provided 40 with belt-pulleys V', the eccentrics G communicate a vertical reciprocating movement to the bar F and sliding bars D D', whereby the needles C are alternately raised and depressed. During the upward travel of the 45 needles the yarn-carrier I is moved forward by the action of the cams n, so that the needles engage the strands of yarn, and the yarn-carrier and the sliding bars D D' are moved endwise at the termination of the downward 50 movement by the bar J, which is acted on by the plate K of the pattern mechanism, so that one needle drops out of action at one end and a fresh needle is brought into action at the opposite end, when, after the bar D' has depressed the needles, the next upward movement takes place. On the downward movement of the needles the loops formed on the needles, and which are released by the closing of the latches, are drawn off by the hooked 55 comb. A pair of rollers may be fitted in front of the machine to draw off the fabric as it is knitted. When the yarn-carrier moves longitudinally with the raising-bar, as many 60 needles may need to be employed as there are 65 needles raised at each action, and as the needles toward the center of the machine are thus oftener raised than those toward the ends a

greater number of courses would be knitted off at or near the central part of the length of the needle-bar than at or near the ends, which are only reached once at every full to-and-fro movement of the raising-bar, and there is produced a series of pieces which, when seamed longitudinally, form "balloons" or cylinders with conical ends, which may be cut transversely or otherwise to produce from each two complete caps. By suitably setting the pattern mechanism, however, to impart a to-and-fro movement of the yarn-carrier I to the extent only of the breadth of one needle and leaving the raising and depressing bars unacted on by the pattern mechanism a continuous length or web of plain knitted work will be produced.

Any fashioned work intermediate between 85 the balloons and plain webs may be obtained by varying the action of the pattern mechanism, variety in ornament and design of the work being also attainable by the use of variously-colored strands of yarn.

Having thus described my invention, what I claim as new therein, and desire to secure by Letters Patent, is—

1. The combination, in a warp-knitting machine, of the framing having a main shaft, a needle-bar, needles, raising and depressing bars having connection with each other, a bar F, eccentrics G, straps or rods g, whereby said bar F is operated through the main shaft, bar J, having connection with the raising and depressing bars, a yarn-carrier connected with the bar J, swinging mechanism for the yarn-carrier, and pattern mechanism whereby endwise movement is communicated to the yarn-carrier and the raising and depressing bars through bar J, substantially as set forth.

2. The combination, in a warp-knitting machine, of the framing having a main shaft, a needle-bar B, needles, raising and depressing bars D D', having connection with each other, a bar F, mechanism for operating the latter from the main shaft, bar J, having connection with the bars D D', yarn-carrier I, connected with the bar J, swinging mechanism for the yarn-carrier, and pattern mechanism whereby endwise movement is communicated to carrier I and bars D D' through bar J, substantially as set forth.

3. The combination, in a warp-knitting machine, of a framing having a main shaft, a needle-bar B, needles, raising and depressing bars D D', a bar F, means connected with the main shaft and bar F for imparting vertical movement to the latter and bars D D', bar J, having connection with the bars D D', yarn-carrier I, connected with the bar J, swinging mechanism for the yarn-carrier, a pattern-plate K, and means for imparting movement to the latter, substantially as and for the purpose set forth.

4. In a warp-knitting machine, the combination of a needle-bar B, needles, bars D D', having vertical movement, means for accomplishing said movement, laterally-movable

yarn-carrier I, swinging mechanism for the latter, and pattern mechanism for imparting endwise movement to bars D D' and yarn-carrier I, substantially as set forth.

5. In a warp-knitting machine, the combination of a needle-bar B, needles, bars D D', means for imparting vertical movement thereto, link j, yarn-carrier I, swinging mechanism for the latter, bar J, a link-connection between the carrier I and bar J, a pattern-plate K, means carried by said bar J upon which the latter is adapted to act and operate bars D D' and yarn-carrier I through bar J, and means for imparting movement to said plate, substantially as set forth.

6. In a warp-knitting machine, the combination of a compound vertically-reciprocating raising and depressing bar consisting of parts D D' d d' and connecting-strap E, means for imparting vertical movement to said bar, pattern mechanism, and mechanism intermediate of the pattern mechanism and said compound bar whereby lateral movement is imparted thereto, substantially as set forth.

25. 7. In a warp-knitting machine, the combination of a compound vertically-reciprocating raising and depressing bar consisting of the parts D D' d d', a strap connecting the parts of said bar, means for imparting vertical movement to said bar, a pattern-plate K, having means of connection with said bar, and means for imparting endwise movement to plate K, substantially as set forth.

35. 8. In a warp-knitting machine, an extensible depressing-bar consisting of the parts D³ D³ d', means for adjustably connecting them, the parts D³ D³ having each a yielding end piece d², and a spring d³, substantially as and for the purpose set forth.

40. 9. In a warp-knitting machine, a pattern mechanism consisting of the plate K, having a stepped slot k, pins k', the driving-piece L', the shaft m, the rotating cam M, eccen-

tries l⁶, spears l⁵, said eccentrics constituting means for reciprocating the latter, blocks l⁴, rods l³, for acting on the latter, cranks l², the latter being acted on by said blocks, and rods l¹, substantially as set forth.

10. In a knitting-machine, the combination, with a series of needles, a bar or bars for moving the same to knit, and the yarn-carrier having a series of yarn-guides for supplying yarn to the needles, of means for moving said bar or bars and yarn-carrier endwise along the series of needles, substantially as and for the purpose described.

11. In a knitting-machine, the combination, with a series of movable needles, a bar or bars for moving the same to knit, said bar or bars being adjustable in length to vary the number of needles brought into action, and a yarn-carrier having a series of yarn-guides for supplying yarns to the needles, of means for moving said bar or bars endwise along the series of needles, substantially as and for the purpose set forth.

12. In a knitting-machine, the combination, with a series of movable needles, a bar or bars for moving the same to knit, and a yarn-carrier having a series of yarn-guides for supplying yarns to the needles, of a frame with which the yarn-carrier and needle-actuating bar or bars are connected to move endwise, and means for moving said frame, substantially as and for the purposes described.

In witness whereof I have hereunto set my hand and seal this 16th day of November, 1886.
